(57) **CLAIM**

The ornamental design for a shoe bottom cleansing apparatus, as shown and described.

DESCRIPTION

FIG. 1 is a top perspective view of a shoe bottom cleansing apparatus illustrating my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a rear elevation view thereof;

FIG. 7 is a front elevation view thereof; and,

FIG. 8 is a top perspective view of the shoe bottom cleaning apparatus coupled to an exemplary shoe environment. The broken lines illustrate portions of the shoe bottom cleaning apparatus that form no part of the claimed design. In FIG. 8, the broken lines illustrate an exemplary shoe environment that forms no part of the claimed design.
